STRAIGHT BAR KNITTING MACHINE

Kurt Willi Wickardt, Liverpool, England, assignor to Hosemaster Machine Company Limited, Liverpool, England, a British company

Application April 9, 1951, Serial No. 219,913
In Great Britain April 11, 1950

9 Claims. (Cl. 66—127)

1

The present invention relates to straight bar knitting machines and is especially, although not exclusively, applicable to straight bar knitting machines for the manufacture of ladies' stockings.

More particularly the invention relates to improvements in the driving means for the thread carrier rods of such machines.

In the conventional thread carrier rod driving mechanisms a friction box is mounted upon a main driving bar (known as the friction bar) which is reciprocated by the Coulier mechanism. The Coulier mechanism reciprocates the friction bar over a constant amplitude of movement whilst the friction box is frictionally mounted on the bar and has a plurality of fingers or detent elements connectable with the various thread carrier rods so that the amplitude of movement of the friction box is governed by the stops of the thread carrier rod to which it may at any particular time be clutched. Thus the friction drive is common to all the thread carrier rods and the thread carrier rods can only be reciprocated with one particular amplitude at any particular time unless two separate sets of drive mechanisms are provided.

According to the present invention a thread carrier rod driving means common to a plurality of thread carrier rods is connected or connectable to the respective thread carrier rods through friction clutch means individual to the respective rods.

According to a further feature of the invention thread carrier rods are respectively driven by a plurality of toothed discs or wheels each associated with a thread carrier rod and co-axially mounted upon a common driving shaft to which they are clutched by friction clutches individual to each of such discs or wheels.

According to a still further feature of the invention a plurality of thread carrier rods are connectable and disconnectable to and from individual driving elements associated therewith, which driving elements are driven from a common thread carrier rod driving means through constantly engaged individual friction clutches so that each thread carrier rod can be connected and disconnected to and from its own particular driving element which when connected to its thread carrier rod will slip relatively to the com-

2

mon thread carrier rod driving means as the thread carrier rod reaches its thread carrier stops.

In a preferred form of construction the main driving means consists of a shaft which can be rotated back and forth in opposite directions and bears a plurality of toothed discs or wheels each provided with a friction clutch to enable it to be driven by the shaft. The friction clutch of each of such discs or wheels may resemble a conventional internal expanding brake of a mechanically propelled vehicle. Each of such discs or wheels may, through an idler gear, drive a pinion which can be moved into and out of engagement with a toothed rack on a thread carrier rod. The pinions may be arranged in a row and may be moved into and out of engagement with their respective thread carrier rod by means of bell-crank levers which may be individually controlled by a common cam which can be automatically actuated during the operation of the knitting machine to bring the appropriate thread carrier rods into operation at appropriate times.

The oscillatable main driving shaft may be driven by the engagement of a pinion mounted thereon with a toothed rack which reciprocates back and forth with the slur cock.

The present invention will now be further described with reference to the accompanying drawings which show by way of example one embodiment of the invention and in which:

30 Fig. 1 is a diagrammatic view of certain parts of a straight-bar knitting machine showing certain elements of such a machine,

Fig. 2 is a diagrammatic plan view showing certain parts of a straight-bar knitting machine,

35 Fig. 3 is a sectional view of part of a straight-bar knitting machine showing especially the loop-forming elements and the thread laying and loop-measuring parts,

40 Fig. 4 is a front elevation detail view to an enlarged scale shown as a section on line IV—IV in Figs. 3, and

Fig. 5 is a plan view to an enlarged scale seen in the direction of arrow A in Fig. 3, with certain parts removed for the sake of clarity.

45 In the drawings only sufficient parts of a straight-bar knitting machine as will enable the invention to be described and understood are shown, and other parts well known to those skilled in the art are omitted for the sake of

clarity. In the drawings like reference numerals indicate like parts.

Referring to Figs. 1, 2 and 3, an L-shaped beam 11 carries one or more groups of loop-forming elements, one for each piece of fabric to be knitted on the machine, and each comprising sinker heads 12 with sinkers 22, knockover bars 26 with knockover bits 25, and jackheads 28 with striking jacks 27. Arranged in front of these groups of loop-forming elements and separately supported are needle bars 24 with needles 23. One or more thread carrier rods 15 are slidably carried in guide brackets 13, 14, attached to the L-shaped beam 11 at intervals, so that the rods may be reciprocated parallel to and along the row of needles. Each of these thread carrier rods supports a plurality of thread carrier fingers 16, one for each group of loop-forming elements, which fingers are so shaped as to enable them, during the Coulier motion of the machine, to lay a thread on the sinker noses and behind the needles 23. Each of these thread carrier rods 15 carries two or more abutments 17, 18, (see Fig. 1) which may contact stop slide 19 supported in a stop-housing 20, which is fixed to the main frame of the knitting machine. The abutments 17, 18 are arranged and adjusted so as to limit the stroke of the reciprocating movement of thread-carrier rods 15 to obtain a desired and pre-determined width of fabric.

Behind and parallel to L-shaped beam 11, a guide-rail 30 supported on the main frame of the machine, carries a number of slurcocks 29, one for each group of loop-forming elements. Slurcocks 29 are slidable on guide-rail 30 and are connected one to another and to a sliding block 39 by a connecting rail 31. A cam-follower 38 rotatably fixed to slideblock 39 engages a helical groove 37 formed in the surface of a drum-shaped cam 36, which is attached to a drive-shaft 35 in order to rotate therewith. Axial movement of drive shaft 35 and drum cam 36 is prevented by collars 72, 73 co-operating with parts of the main frame of the knitting machine. Fixed to drive shaft 35 is any suitable place is a drive gear 34 engaging a pinion 33 attached to the shaft of an electric motor or other prime mover 32.

It will be understood that during any whole revolution of drive shaft 35 slurcocks 29 will be reciprocated along the groups of loop-forming elements. The stroke of groove 37 has to have an amplitude of suitable size to move the slurcocks 29 through a distance slightly more than the width of each knitting section. This movement of slurcocks 29 results in striking jacks 27 being brought forward into contact with the butts of sinkers 22 thus moving sinkers 22 forward to bring their front ends or noses into positions enabling them to measure kinks of loops against needles 23.

Referring now more particularly to Figs. 3, 4 and 5, attached to connecting rail 31 and sliding on guide-rail 30 are two support-brackets 40, 41 carrying a toothed rack 42, which rack takes part in any reciprocating movement of connecting rail 31 and slurcocks 29. A spur-gear 43 is supported by a shaft 44 which is rotatably carried in a housing 45 attached to the main frame of the knitting machine. It will be understood that shaft 44 performs an alternating rotary movement during any reciprocating movement of rack 42 and slurcocks 29.

Inside housing 45, shaft 44 carries a number of clutch mechanisms 46, one for each thread-

carrier rod to be reciprocated along the row of needles. Each of these clutch mechanisms 46 consists of two side flanges 49, 50, fixed to shaft 44 by means of a key 52 in order to take part in any rotary movement of shaft 44. Side flanges 49, 50 support rotatably a friction ring 51. Inside friction ring 51 is arranged a pair of friction levers 54 supported on a pin 53 in side flanges 49 and 50. A compression spring 55 presses friction levers 54 against the inner side of friction ring 51.

Friction levers 54 take part in any rotary movement of side flanges 49, 50 and shaft 44, while the friction between friction levers 54 and friction ring 51 causes said friction ring to take part in such rotating movement until any further rotation of said friction ring is prevented as will be hereinafter described and friction levers 54 will then slide along the inner side of friction rings 51.

Spur gear teeth cut into the outside of friction rings 51 engage teeth of idler gears 47, rotatably supported on a shaft 56 in housing 45, there being one idler gear 47 for each clutch mechanism 46. The torque of each idler gear 47 is transmitted to one of pinions 48 which are individually supported on pins 57 in vertical slides 58. Slides 58 are slidably supported in housing 45 one above each thread carrier rod to be operated, thereby enabling each of pinions 48 to be moved individually in a vertical direction into either the inoperative position in which it is disengaged from rack 21 attached to the associated thread carrier rod 15, or into the operative position 48a in which it engages the rack 21 attached to the associated thread carrier rod 15.

The upper end of each of said vertical slides 58 carries an extension 59 engaging the forked end of one of a group of bell-crank levers 60 rotatably supported on a shaft 62 in housing 45. The other or vertical ends of bell-crank levers 60 are arranged and shaped in a way to enable them to be brought into contact with cam studs 71, attached to a control drum 64. Compression springs 61 or other suitable means are individually arranged for each of bell-crank levers 60 so as to press the upper ends of said bell-crank levers towards control drum 64, thus urging associated slide 58 and pinion 48 in their upper or inoperative positions.

Control drum 64 is attached to a control shaft 65, which is rotatably supported in housing 45 and carries firmly attached to itself a ratchet wheel 66. An oscillatable lever 67, which carries a pawl 68 which is prevented from slipping off its supporting pin by a collar or other suitable means 69, is freely carried on control shaft 65. The lower end of lever 67 may be connected by a connecting rod 70 in a way well-known in the design of straight-bar knitting machines to a cam follower operated by a cam on the cam shaft of the machine. Lever 67 may thus be operated at pre-determined selected intervals to bring about partial rotation of control drum 64 in steps. Cam studs 71 are arranged on control drum 64 in suitable places so that each may engage the upper or vertical end of a bell-crank lever 60 in order to bring one or more of said bell-crank levers into its operative position 60a against the action of compression spring 61, thus bringing one or more of pinions 48 into its operative position in engagement with one or more of racks 21 attached to thread carrier rods 15.

As indicated in the accompanying drawings, cam stud 71a on control drum 64 contacts the upper end of bell-crank lever 60a, thus bringing pinion 48a into engagement with rack 21a, out of a group of racks 21, attached to thread carrier rods 15. During the first half of a revolution of shaft 35 in the direction of arrow B in Fig. 2, slide block 39, slur cocks 29 and rack 42 are moved to the right as seen in Fig. 2, the amplitude of which movement is controlled by groove 37 in drum cam 36. Gear 43 and shaft 44 consequently are rotated in the direction of arrow C in Fig. 2, resulting in movement of rack 21a and its corresponding thread carrier rod to the right until abutment 18 contacts stop slide 19 in stop housing 20. Friction ring 51 is now prevented from taking part in any further rotation of shaft 44 and friction levers 54 will slide inside friction ring 51 until the movement of rack 42 and slurcocks 29 to the right has reached its end. During the next half revolution of shaft 35 and drum cam 36, in the direction of arrow B in Fig. 2, slurcocks 29 and rack 42 are moved to the left as seen in Fig. 2, resulting in rotation of gear 43 and shaft 44 in the direction opposite to that shown by arrow C in Fig. 2. Rack 21a and its corresponding thread carrier rod 15, is now moved to the left until abutment 17 contacts stop slide 19 in stop housing 20, from which moment a sliding movement between friction levers 54 and friction ring 51 occurs as described above.

It will be readily understood that by this application of the present invention to a straight-bar knitting machine, each of a group of thread carrier rods can individually be brought into timed relation with the movement of the slurcocks, while the remaining thread carrier rods are unaffected and may remain stationary.

I claim:

1. In a straight bar knitting machine embodying a plurality of reciprocable thread carrier rods and thread carrier stops for limiting the travel of said thread carrier rods, a driving shaft common to a plurality of thread carrier rods, power drive means for oscillating said shaft back and forth in opposite directions of rotation, a plurality of toothed wheels mounted on said shaft and each associated with one of the thread carrier rods, a friction clutch for each of said toothed wheels for frictionally coupling said toothed wheels with said shaft, and means between said toothed wheels and said thread carrier rods for selectively establishing a driving relationship between said toothed wheels and their respective thread carrier rods and for interrupting such driving relationship.

2. In a straight bar knitting machine according to claim 1, cam means common to all of the thread carrier rods adapted to individually interrupt and restore the driving relationship between said subsidiary driving elements and said thread carrier rods.

3. In a straight bar knitting machine embodying a slur bar, power drive means for reciprocating said slur bar, a plurality of rack toothed reciprocable thread carrier rods, thread carrier stops for respectively limiting the travel of the thread carrier rods, a toothed rack on said slur bar, a driving shaft common to a plurality of thread carrier rods, a toothed wheel on said shaft in engagement with said rack to enable reciprocation of the slur bar to rotate said shaft to and fro, a plurality of toothed wheels mounted on said shaft and each associated with one of

the thread carrier rods, a friction clutch for each of said toothed wheels for frictionally coupling said toothed wheels with said shaft, and means between said toothed wheels and said thread carrier rods for selectively establishing a driving relationship between said toothed wheels and their respective thread carrier rods and for interrupting such driving relationship.

4. In a straight bar knitting machine, a plurality of rack toothed reciprocable thread carrier rods, thread carrier stops for respectively limiting the travel of said thread carrier rods, a driving shaft common to a plurality of thread carrier rods, means to oscillate said shaft back and forth in opposite directions of rotation, a plurality of toothed wheels mounted on said shaft and each associated with one of the said thread carrier rods, a friction clutch for each of said toothed wheels for frictionally coupling said toothed wheels with said shaft, a set of pinions driven respectively by said toothed wheels and adapted respectively to be moved into and out of engagement with said rack toothed thread carrier rods, cam means for individually controlling the engagement and disengagements of said pinions with the rack toothed thread carrier rods, and pivoted lever elements between said cam means and said pinions for displacing the pinions into and out of engagement with the rack toothed thread carrier rods under the control of said cam means.

5. In a straight bar knitting machine according to claim 4 a toothed idler between each of said toothed wheels and its related pinion.

6. In a straight bar knitting machine according to claim 4 and embodying a reciprocating slur bar, a toothed rack on said slur bar and a pinion on said driving shaft in engagement with said rack to enable the oscillation of the shaft to be achieved by the reciprocation of the slur bar.

7. In a straight bar knitting machine according to claim 4, a separate toothed rack element secured to each thread carrier rod for engagement for its pinion.

8. In a straight bar knitting machine, a plurality of rack toothed reciprocable thread carrier rods, thread carrier stops for respectively limiting the travel of said thread carrier rods, a driving shaft common to a plurality of thread carrier rods, means to oscillate said shaft back and forth in opposite directions of rotation, a plurality of toothed wheels mounted on said shaft and each associated with one of the said thread carrier rods, a friction clutch for each of said toothed wheels for frictionally coupling said toothed wheels with said shaft, a set of pinions driven respectively by said toothed wheels and adapted respectively to be moved into and out of engagement with said rack toothed thread carrier rods, and cam means for individually controlling the engagement and disengagement of said pinions with the rack toothed thread carrier rods.

9. In a straight bar knitting machine a plurality of reciprocable thread carrier rods, thread carrier stops for limiting the travel of said thread carrier rods, a common rotary driving element for driving said thread carrier rods, power drive means for oscillating said common driving element back and forth in opposite directions of rotation, a plurality of subsidiary driving elements co-axial with said common rotary drive element, one of said subsidiary driving elements being provided for each thread carrier rod, individual frictional driving means for driving each of said

subsidiary driving elements from said common driving element, gearing means individual to each of said subsidiary driving elements and each movable into and out of an operative position, each gearing means in said operative position connecting one of said subsidiary driving elements with an associated thread carrier rod and when not in said operative position disconnecting said subsidiary driving element from said associated thread carrier rod, and means for selectively moving said gearing means individually into and out of said operative positions to selec-

tively establish and interrupt driving relationship between said subsidiary driving elements and said thread carrier rods.
